US0D1067754S

(12) **United States Design Patent** (10) **Patent No.:** **US D1,067,754 S**
(45) **Date of Patent:** **** Mar. 25, 2025**

(54) **HOLDING DEVICE**

- (71) Applicant: **SHENZHEN HAOHUALIANHE TECHNOLOGY CO., LTD.,**
Guangdong (CN)
- (72) Inventor: **Weihao Chen**, Shenzhen (CN)
- (73) Assignee: **SHENZHEN HAOHUALIANHE TECHNOLOGY CO., LTD.**, Shenzhen (CN)
- (**) Term: **15 Years**
- (21) Appl. No.: **29/765,829**
- (22) Filed: **Jan. 12, 2021**

(30) **Foreign Application Priority Data**

Aug. 1, 2020 (CN) 202030431119.0

(57) **CLAIM**

The ornamental design for a holding device as shown and described.

DESCRIPTION

FIG. 1 is a front, right side perspective view of a holding device, showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines and low-saturation areas shown in the figures illustrate portions of the holding device that form no part of the claimed design.

1 Claim, 7 Drawing Sheets
